UNITED STATES PATENT OFFICE

2,558,539

MEDICAL RADIOGRAPHIC APPARATUS

Sylvain Chaussé, Paris, France

Application June 3, 1950, Serial No. 166,009
In France June 6, 1949

5 Claims. (Cl. 250—65)

1

The advances made in methods of X-ray photography examination produce an increasing demand for radiographic apparatus in which there is provision for an ever greater number of different movements.

I have previously described an apparatus more especially designed for use in connection with that method of X-ray examination sometimes known as Dr. Chaussé's method, and which applies a now broadly known procedure.

That apparatus, which was a considerable improvement over prior devices of similar type, essentially comprised a table rotatable about a horizontal axis and provided with an image-carrier supported on longitudinally and transversely traversing carriage, an X-ray lamp mounted at the end of a balance-beam movable longitudinally by the oscillation of parallel arms rotatable about the same axis as said table, and a connecting means from said lamp to said image-carrier, operative, regardless of the angular orientation of the lamp, to direct the X-ray beam onto a given point of the image. Owing to the dual movement of the image-carrier along two rectangular directions of the table, the said connecting means were somewhat intricate and delicate to construct. Moreover, no means were provided for altering the particular point of coincidence provided by said connecting means.

It is an object of this invention to provide a medical radiographic apparatus which enables any examination to be effected and new photography or adjusting operations to be performed, extremely handy to operate and of cheaper and more rugged construction.

According to the invention, the apparatus comprises a box-shaped casing, rotatable about a horizontal axis, a transversely movable operating table supported on said casing, within said casing an image-supporting carriage movable along said axis, a connecting rod, a cardan-joint connecting said carriage with said rod, a bar carrying at one end thereof the X-ray lamp pivoted thereon, said bar being slidable parallel to the axis of said table in a support rotatable about said axis, said bar carrying a pin on which a slot of said connecting rod is slidable, said connecting-rod being further pivoted at an intermediate point thereof about a transverse axis rigid with said support, said pivotal lamp being itself connected to a cardan rigid with said carriage through a directing rod slidable parallel to said connecting rod and constituting therewith a parallel linkage system, said directing-rod curving downwardly and inwardly beneath said table

2

and terminating in a spotlight adapted to direct a centring ray towards the X-ray beam.

The cardan of the connecting rod is connected with the cardan of the directing rod by a connection fixed in length and is connected to the carriage by a coupling which may be fixed or variable in length. The cardan joint of the connecting rod preferably comprises a core member journaled on the transverse pins of a clevis provided at the end of the connected rod, said core members being mounted for rotation on a bushing, said bushing being setably slidable on an axis coupling rod rigid with said carriage and secured in a lateral stirrup carrying a bar for connection with the cardan joint of the directing rod.

The connecting rod is slidable in a tube pivoted through transverse journals in a clevis provided at the end of an adjusting rod parallel to the axis of the table and carried on a radial carriage of the support of the lamp-carrying bar. Said adjusting rod is screwed into a bushing slidable in the carriage and longitudinally blockable to serve as a nut for imparting longitudinal displacement of the adjusting rod.

The X-ray lamp is mounted in a vertical stirrup slidable and movable by means of a screw in another vertical stirrup which can rock in a horizontal stirrup secured at the end of the lamp-carrier bar and is rigid with a bushing in which the directing rod is slidable.

The above and further objects, features and advantages of the invention will all be clearly understood from the ensuing description made with reference to the accompanying drawings, in which

Figures 1 and 2 are side and end elevational views, respectively, of the apparatus as a whole;

Figures 3 and 4 are a longitudinal section and an overhead plan, respectively, of the casing rotatable on a horizontal axis and carrying the operating table;

Figure 5 is a fragmentary view on an enlarged scale of that part of Figure 1 which comprises the connection from the casing to the lamp-carrying bar, with a partial section on a longitudinal vertical plane;

Figure 6 is a corresponding view in section on line VI—VI of Figure 5;

Figure 7 is a section on line VII—VII of Figure 5;

Figure 8 is a horizontal section on the line VIII—VIII of Figure 5;

Figures 9 and 10 illustrate a detail of the pivotal connection between the connecting rod and

the lamp-carrier bar, respectively in elevation and in section on the line X—X of Figure 9;

Figure 11 is a partial view in transverse cross-section similar to Figure 6 but made on the line XI—XI of Figure 3; and

Figures 12 and 13 are, respectively, an end elevation and a plan, with parts broken away, of the stirrups carrying the lamp.

As shown in Figures 1 and 2, the frame of the apparatus comprises a conventional telescopically expandible standard or support 1 the slidable post 2 of which terminates in a head 3 forming a bearing for a horizontal shaft which on one side (left as in Figure 1) carries the operating table 4, and on the other side a structure serving to support the X-ray lamp 5 above the table 4.

On the table side (see also Figures 3 to 5) the horizontal shaft 6 which, as visible in Figure 3, is tubular, is fitted into an elongated bushing 7 projecting from a box-shaped casing 8 serving to support the table. On a bearing at the outer end of said bushing there is secured a ratchet wheel 9 provided with deep-cut teeth formed with bevelled sides, adapted to be engaged by a pawl 10 thus serving to block the casing, said pawl being provided by a long lever pivoted on a lug 11 formed on the head 3 of the standard and provided with a set-screw 12, by means of which the pawl can be blocked in position in the bottom of a space between any two teeth of the ratchet 9.

The casing 8, in the part thereof away from the standard, supports the plate which forms the operating table 4, said table being slidable on transversely-extending rails 13 secured to the side edges of the casing so as to be slidable at right angles to the longitudinal axis. It is noted that throughout the ensuing disclosure, the expression longitudinal axis will refer to the axis of the shaft 6 which, as stated later, lies in the same plane as the X-ray photograph or image located under the table. On one side of this table there is secured a nut 14 engaging a transversely-extending worm 15 which is passed through a cutout formed on the rear side of the casing, and journaled on the opposite side of said casing and geared through meshing pinions 16 to a stub-shaft carrying a handwheel 17. The surface of the table is formed with two windows, one, 18, of which is closed by a translucent cover plate on which squared cross-rules are drawn to serve as a reference panel, while the other window 19, equal in size to 18, is covered by a supporting plate made of a material permeable to X-rays, and beneath which the X-ray photograph is movable; the photograph is housed in a flat box 20 having a handle 21 which projects beyond the end of the table through an opening formed in the end wall of the casing.

The flat box 20 is engaged in a longitudinally extending slideway 22 formed on a carriage which comprises a frame 23 slidable between suitable ribs formed on the sides of the casing (also see Fig. 11) above a window 25 formed in the bottom wall of the casing. The box 20 is adapted to be blocked at any desired point along said slideway by means of a conventional pawl-and-ratchet device or the like. The carriage frame 23 has secured to it (see Fig. 3) a coupling rod 26 extending along the longitudinal axis and slidable in a bearing boss formed on an intermediate transverse partition 27 which divides the casing lengthwise into two compartments 28 and 29 and is further slidable in a hole formed in the end wall 30 of the bushing 7 through which the casing is secured on the shaft 6. The bottom

wall of the casing in the compartment 29 thereof of supports, in a position below the reference panel 18, a number of electric bulbs 31 providing as many light sources for illuminating said panel in such a way that the rod 26 will not cast any troublesome shadow thereon. The partition 27 prevents the light from penetrating into the compartment 28 that contains the photograph. The lamps 31 are supplied with current through conductors 32 extending through the tubular shaft 6. On the rod 26 and spaced from the centre of the photograph by a distance equal to the spacing between both windows in the table, there is secured a collar 33 carrying a reference index, preferably in the form of a sighting mark 34; it will be seen that the longitudinal displacements of the index 34 will correspond to those of the photograph.

That part of the shaft 6 that lies on the other side from the top bearing 3 of the standard (see Figs. 1 and 5) serves as a pivot for a bushing 35 adapted to be blocked on said shaft by means of a set screw provided with a hand-wheel 36. At the opposite ends of the bushing 35 there are secured a pair of parallel arms 37 and 38 and the bushing is retained on the shaft 6 by means of a lock-nut assembly 39 engaging the threaded end of the shaft. The arms 37 and 38 provide supporting elements for the lamp, the supporting structure being balanced by a counterweight 40 secured between the lower extensions of the arms. At their ends opposite from this balancing weight the arms 37 and 38 terminate in enlarged heads formed with aligned square bearing apertures therein, in which a hollow lamp-carrier bar 41 of complementary square section is slidable parallel to the longitudinal axis, preferably through the medium of suitable roller bearings. The lamp carrier bar 41 is blockable in any selected longitudinal position by means of a set-screw provided with an operating knob 42.

The bar 41 is set at an angle, i. e., with the diagonal planes of its square cross section lying in horizontal and vertical directions, and is formed, at a point of its projecting length, with opposite vertical flattened areas, as more clearly visible in Figures 9 and 10. This flattened or depressed portion is formed with a bore through which extends a stub-shaft 44 inserted through a spacer bushing 43, the end journals of the stub shaft 44 being each journaled in a part comprising a flange 45 applied flat against the bar surface and a rectangular boss 46 forming a slideblock. The opposite slideblocks 46 are each engaged in a slideway formed in a related one of the arms of a yoke or clevis member 47 having its top or free end closed by an end spacer strip 48. Said clevis is secured to the top end of a connecting rod 49 which connects the lamp-carrier bar to the coupling rod 26.

The connecting rod 49 is slidable at an intermediate point of its length (see Figs. 1 and 6) in a tube 50 pivoted at the end of an arcuate yoke or clevis 51 which curves down towards the casing and is secured at the end of an adjusting rod 52 supported by the adjacent arm 37. The rod 52 (also see Figs. 5, 7 and 8) is threaded at its end and is screwed into a bushing 53 terminating in a hand-wheel 54. This bushing is mounted for sliding movement in a slideblock 55 and can be blocked against longitudinal movement relatively thereto, in a position in which an end flange 56 of the bushing is in abutting engagement against the end wall of the slideblock (see Fig. 8), by means of a set-screw 57

provided with a knurled head, said screw engaging an annular groove formed in the bushing; the bushing in its thus blocked condition will serve as a rotary nut imparting longitudinal displacement of the adjusting rod 52.

The slideblock 55 is formed as a shouldered block square in cross-section, and is mounted within the arm 37 from which it projects through oppositely located apertures 58 formed in said arm. To enable assembly of the slideblock the hollow arm 37 is divided along a transverse plane and built up again to its original cross-sectional form by means of a cover shell 59 secured by means of screws, not shown. Inside the hollow arm, the slideblock is formed with a threaded hole engaging a worm 60 journalled at each end in a related one of a pair of half-bosses 61 respectively integral with the arm and the cover. At its lower end the worm carries a helical pinion 62 meshing with a worm 63 provided with an externally projecting handwheel 64.

The bottom of the connecting rod 49 (see Figs. 3, 4, 5 and 6) is connected through a cardan joint with the coupling rod 26, the connection including a clevis 65 pivoted on the opposite transverse journals of a core member 66 rotatable about the rod 26. The core is engaged between the arms 67 of a horizontal stirrup, the end wall 68 of which forms a slideblock slidable in the slideway or slot formed in the rear of the casing 8. The core is mounted for rotation on a bushing 69 secured to the stirrup by a screw 70, and is split and internally threaded at its opposite end to be clamped about the rod 26 by means of a knurled rod 71. Against the outer surface of the end wall of the stirrup member 67 there is secured the flattened end of a directing rod 72, curved so as to deviate away from the vertical plane of the rear edge of the operating table. This rod at its end (Figs. 2 and 11) is connected through a cardan joint with a directing rod 73 adapted to orient or direct the X-ray lamp in a direction parallel to the connecting rod. The cardan joint comprises a core member secured to the rod 73 and pivoted on longitudinal journals in a collar 74 pivoted in turn on transverse journals in a clevis 75 terminating the rod 72.

The rod 73 is in the form of an arcuate tube curving down and in under the table and carrying at its end (Fig. 3) a spotlight projector 76 serving to materialize as a spot of light the direction of the X-ray beam. The supply conductors 77 for this spotlight extend through the tubular rod 73 and through the lamp-carrier bar. At its top the director rod 73 slides in a bushing 78 carried on the rear side of a vertical stirrup 79 (see Figs. 12 and 13) pivoted on journals 80 between the arms of a horizontal stirrup 81 blocked on the end of the square hollow bar. Within the vertical stirrup 79 a further stirrup 82 is mounted, provided with lateral slideblocks 83 guided in longitudinal slots in the internal faces of the arms of the outer stirrup 79, and engaging a screw 84 rotatable in freely suspended condition from said stirrup 79 and provided with a hand-wheel 85. The inner stirrup 82 supports between its arms the X-ray lamp 5. This lamp is adapted to be displaced for its focussing adjustment by imparting a sliding movement to the inner stirrup. The lamp's supply cable 86 extends through the hollow bar 41.

Calibrated scales and indexes or the like, not illustrated, make it possible to identify and measure the required displacements.

It will be seen that the operating table is adapted to receive any desired inclination about its longitudinal axis, by rotating the casing after having released its pawl-blocking means, that is to say, by rotating the horizontal shaft 6. The table is retained in the desired position by the pawl 10 being blocked with the screw 12. The casing and the shaft are thus rendered stationary and the shaft will serve as a pivotal axis for the balanced lamp-supporting structure, which it thus becomes possible to block in any desired angular position by means of the handwheel 36. The square bar 41 slides freely in a longitudinal direction between the roller bearings in the heads of the arms 37 and 38 and may be blocked with the handwheel 42. Movement of the bar is accompanied by rotation of the connecting rod about the intermediate fixed fulcrum provided by the journals of clevis 51 of the adjusting rod 52. The vertical height of this fulcrum above the longitudinal axis is adjustable by rotation of the hand-wheel 64 adapted to move the slideblock 55 within the hollow arm and it is further adjustable in longitudinal position by rotation of the hand-wheel 54, after the bushing has been blocked against longitudinal movement by engagement of the set-screw 57 provided with an actuating wheel. During rotation of the lamp support about the longitudinal axis, the connecting rod 49 rotates with its cardan core 66 about the coupling rod 26 directed along this axis. When the connecting rod is pivoted about its intermediate fixed fulcrum, if the block nut 71 of the bushing of cardan core 66 is screwed tight, then this core is made rigid with the coupling rod 26 which consequently will be driven and will displace the carriage in a longitudinal direction, any differences in length resulting from the inclination of the connecting rod being taken up by the sliding-movements of the rod itself within the bushing 50 and that of its terminal clevis 47 over the slideblocks 45. If the nut 71 is loosened, the cardan core will move without driving the carriage. However, its displacements are always accompanied by an equal displacement of the cardan of directing rod 73, said thus retaining a direction parallel to the connecting rod and sliding in the bushing 78. Consequently, when the cardan core member 66 is blocked on the rod, the X-ray beam or the beam from the locating spotlight 76 at all times extends through a definite point of the photograph. Its displacement within the frame of window 19 is equal in extent to the displacement of the sighting-mark beneath the reference panel. The sighting mark is located as close as possible to the panel in order to reduce parallax error. The vertical displacements are effected by moving the operating table transversely to the casing, through actuation of the handwheel 17.

It will thus be seen that the above described apparatus allows any desired radiographical operation to be accomplished. For this purpose, the patient's head is held on the operating table after the desired inclination has been imparted to said table.

For radiography in two stages, a first photograph is printed, the print is placed on the reference panel and the requisite correction is effected by a transverse displacement of the table and a longitudinal displacement of the photograph, the displacements of the index being followed on the reference panel.

In stereoscopic radiography and for planigraphic examination (depending on whether it

is desired to make two photographs or on the other hand to operate on a common photographic print), the pivotal fulcrum of the connecting rod is adjusted vertically to the height of the point to be examined; this being possible owing to the arcuate form of the clevis 51. A displacement of the lamp in the longitudinal direction is accompanied automatically by a simultaneous displacement of the photograph, while the X-ray beam remains centered always on the same desired point.

Finally, to perform a locating or "spotting" operation, either the cardan core member may be blocked on the coupling rod and the bushing 53 of adjusting rod 52 left free to slide, or alternatively the bushing may be blocked against longitudinal movement to obtain a fixed intermediate fulcrum and the cardan core released from the carriage rod by loosening the nut 71.

Thus it can be seen that the apparatus described offers great flexibility in operation. It is to be understood however that the invention is not restricted to the particular structural details illustrated and described, and that variations may be made in the illustrative embodiment shown without exceeding the scope of the invention.

What I claim is:

1. A medical radiographic apparatus comprising in combination, a standard with a head forming a horizontal bearing, a longitudinal shaft rotatably mounted in said bearing, means for blocking said shaft, on one side of said standard a box-shaped casing fixed to said shaft, a table transversely slidable on said casing and provided with two longitudinally spaced windows, the one provided with a panel permeable to X-rays, the other with a translucent reference panel, means for transversely adjusting said table on said casing, an image-supporting carriage in said casing below said X-rays panel, adapted to receive a photograph film or plate in a plane parallel to said table and on the axis of said shaft; a longitudinal coupling rod coaxial to the shaft fixed to said carriage and longitudinally slidable therewith, a sighting mark fixed on said coupling rod below said reference panel, on the other side of said standard a support rotatably mounted on said shaft; a lamp-carrier bar longitudinally slid able in said support parallel to said shaft, a lamp supporting structure transversely pivoted at that end of said bar above said table, a connecting rod

10

of variable length attached by a cardan-joint to said coupling rod and by a transverse pivot to said bar, a longitudinal directing rod rigidly connected to said cardan-joint, and a director rod of variable length fixed in direction with said lamp structure and connected by a cardan-joint with said directing rod, said director rod and said connecting rod forming a parallel linkage system between the axes of the shaft and of the bar.

5. A medical radiographic apparatus according to claim 1, in which an extension of said director rod is formed by an arcuate tube curving down and in under the table and carrying at its end 15 a spotlight projector coaxial and opposite to the axis of the X-rays lamp.

3. A medical radiographic apparatus according to claim 1, comprising further a longitudinal adjusting rod intermediate between said shaft and bar, pivoted on a transversal axis to a connection 20 slideable on said connecting rod and longitudinally displaceable, a carriage radially displaceable in said support, means for adjusting radially said carriage, means for longitudinally blocking said adjusting rod and means for longitudinally adjusting the same.

4. A medical radiographic apparatus according to claim 1, in which the cardan-joint between said coupling rod and said connecting rod is setably slideable on said coupling rod.

5. A medical radiographic apparatus according to claim 1, in which the lamp supporting structure is mounted in a horizontal stirrup secured at the end of the lamp-bar and comprises on oscillating stirrup pivoted in said horizontal stirrup, another stirrup rigid with the lamp and slidably mounted in said oscillating stirrup, and means for adjusting said slideable stirrup in said oscillating stirrup.

SYLVAIN CHAUSSE.
